SPRAY SHIELD

Johannes Uytenbogaart and August Hartmann,
Berlin-Lichterfelde, Germany, assignors to
North American Rayon Corporation, New
York, N. Y., a corporation of Delaware

Application April 3, 1936, Serial No. 72,466
In Germany April 8, 1935

9 Claims. (Cl. 18—8)

This invention relates to the manufacture of artificial silk but more specifically has for its object to devise an improved spray shield for use on spinning machines.

5 In the manufacture of artificial silk, rollers which may be driven or rotated solely by the passage of the filaments thereover are used. The purpose of these rollers is to act either as guides or as stretching means for the freshly spun artificial silk filaments. The rollers are rather 10 smaller in circumference and have a high angular velocity which causes the surplus acid of the spin bath carried by the filaments to be thrown off in a spray. Baffle plates or spray shields have 15 been suggested and used for the protection of the spinning machine operator and to facilitate the recovery of the spin bath.

Ordinary spray shields, which are made in the 20 form of solid plates, become incrusted with salt crystals when they are continuously subjected to the spraying from the spin bath liquids. This incrustation of the spray shield may be entirely eliminated if the said shield is continuously and over its entire surface sprayed by a liquid.

25 It is therefore the purpose of the present invention to provide a spray shield which is constantly dispersing the spray over its entire surface by reason of having slots formed in the said shield. The liquid thrown off from the rotating 30 rollers splashes against the slotted shield and a portion of the liquid penetrates through the openings to the opposite side of the shield and a spraying of the said shield takes place on both sides without allowing the spray to be thrown therefrom.

35 The spray shield is also formed in such a manner as to lead back a portion of the sprayed solution to the roller in order that the said roller may revive a constant spray and prevent crystallization thereon.

40 It is therefore one object of the present invention to devise a spray shield which is so designed as to prevent incrustation forming thereon due to crystallization from the spinning solutions.

45 Another object of the present invention is to devise a spray-shield which will lead back a portion of the solution spray to the roller and thus prevent crystallization taking place thereon.

50 These and other objects will in part become obvious and will in part be pointed out herein-after.

To the attainment of the aforesaid objects and ends, the invention consists in the novel features of construction and in the combination,

connection and arrangement of parts, herein-after more fully described, and then pointed out in the appended claims.

In the drawing:

Fig. 1 is a side elevation of the spray shield and in dotted lines is indicated the relative position of the roller which it is intended to shield.

Fig. 2 is a front elevation of the novel spray shield, and

Fig. 3 is a plan view of the perforated blank 10 before it has been bent to form the spray shield comprising the invention.

In the drawing, in which like numerals of reference indicate like parts, 1 indicates, in dotted lines, the freshly spun artificial silk thread which 15 carries the acids and salts. The thread 1 passes rapidly over a rotating roller 2, also shown in dotted lines.

Due to the speed of rotation of the roller the 20 surplus liquid carried by the thread 1 is thrown against the spray shield 3 which prevents the liquids from spraying the operator and adjacent parts of the machine.

The upper portion of the spray shield 3 is bent 25 at an acute angle downwardly and inwardly toward and overhanging the roller 2 and is formed in the shape of two projections 5 and 6 which taper to points where they overhang the roller.

The projections 5 and 6 act to return a portion 30 of the spray to the roller 2 and thus prevent the formation of crystals thereon.

The lower part of the spray shield 3 is formed 35 as a clamp 7 whereby it may be slipped over a supporting arm or strut (not shown) of a spinning machine.

As shown in Figs. 2 and 3 this clamp 7 may be formed in one piece with the rest of the spray shield.

The openings 8 in the spray shield may be of 40 various shapes other than the parallel slots illustrated in the drawing.

The essential feature of the openings is to 45 make them narrow enough that the spray is prevented from being thrown through while allowing a constant seepage to take place as the solution flows down the inner side of the shield 3. By sloping the slots 8, as illustrated, the seepage of liquid to the outside is facilitated.

From the foregoing description, taken in connection with the accompanying drawings, it is 50 thought the complete construction, operation and advantages of the invention will be clear to those skilled in the art to which it relates.

What is claimed is:

1. In combination, a rotatable element from 55

- which liquid may spray and a shield to intercept said spray, said shield comprising an upstanding portion having openings formed therein to allow a portion of the intercepted liquid to pass to the opposite side of said shield, and an upper portion bent at an acute angle and extending downwardly to and overhanging said rotatable element.
2. In combination, a rotatable element from which liquid may spray and a shield to intercept said spray, said shield comprising an upstanding portion having openings formed therein to allow a portion of the intercepted liquid to pass to the opposite side of said shield and an upper portion bent at an acute angle, said bent portion comprising tapered projections extending downwardly and overhanging said rotatable element.
3. In combination, a rotatable element from which liquid may spray and a shield to intercept said spray, said shield comprising an upstanding portion and an upper portion comprising tapered projections having openings formed therein to allow a portion of the intercepted liquid to pass to the opposite side of said shield, said projections being bent at an acute angle and extending downwardly to and overhanging said rotatable element.
4. In combination, a rotatable element from which liquid may spray and a shield to intercept said spray, said shield comprising an upstanding portion having parallel slots formed therein which are at an angle to a horizontal plane to allow a portion of the intercepted liquid to pass to the opposite side of said shield, and an upper portion bent at an acute angle, said bent portion comprising tapered projections extending downwardly and overhanging said rotatable element, said projections having slots formed therein to allow a portion of the intercepted liquid to pass to the opposite side of said projections.
5. In combination, a rotatable element from which liquid may spray and a shield to intercept said spray, said shield comprising an upstanding portion having parallel slots, which are at an angle to a horizontal plane, formed therein to allow a portion of the intercepted liquid to pass to the opposite side of said upstanding portion, and an upper portion bent at an acute angle and extending downwardly to and overhanging said rotatable element, said bent portion comprising tapered projections extending downwardly to and overhanging said rotatable element, said projections having slots formed therein to allow a portion of the intercepted liquid to pass to the opposite side of the said projections and a bracket member formed integral with said upstanding portion.
6. In combination, a rotatable element from which liquid may spray and a shield to intercept said spray, said shield comprising an upstanding portion having openings formed therein to allow a portion of the intercepted liquid to pass to the opposite side of said upstanding portion and an upper portion bent at an acute angle thereto, said upper portion consisting of tapered projections extending on either side of said rotatable element and ending directly above the axis of said rotatable element.
7. In combination, a rotatable element from which liquid may spray and a shield to intercept said spray, said shield comprising a main body portion, and tapered portions projecting beyond said body portion and extending downwardly to said rotatable element and on either side thereof, said tapered portions ending directly above the axis of said rotatable element.
8. A spray shield comprising an upstanding main body portion having slots extending substantially in horizontal direction, and an upper portion inclined downwardly from said main body portion and having slots extending substantially longitudinally of the upper inclined portion.
9. A spray shield comprising an upstanding main body portion having parallel slots which are at an angle to a horizontal plane, an upper portion inclined downwardly from the upper end of said main body portion and having slots extending substantially longitudinally of the upper inclined portion, and a bracket member formed integral with said main body portion.
